UNITED STATES PATENT OFFICE

172,374

DRY CHEMICAL WHEELED FIRE EXTINGUISHER

Franz Wagner, Chicago, Ill., assignor to Ansul
Chemical Company, Marinette, Wis., a corpora-
tion of Wisconsin

Application December 1, 1953, Serial No. 27,860

Term of patent 14 years

(Cl. D16—2)

To all whom it may concern:

Be it known that I, Franz Wagner, a citizen of the United States, residing at 444 North Michigan Avenue, Chicago, Illinois, have invented a new, original, and ornamental Design for a Dry Chemical Wheeled Fire Extinguisher, of which the following is a specification, reference being had to the accompanying drawing forming a part thereof, in which:

Figure 1 is a front view of the dry chemical wheeled fire extinguisher showing my new design,

Figure 2 is a left-hand side view thereof,

Figure 3 is a rear view thereof, and

Figure 4 is a plan view thereof.

I claim:

The ornamental design for a dry chemical wheeled fire extinguisher, as shown.
